MECHANICAL BAND SPREAD FOR RADIO
TUNING

Charles F. Mathewson, Buffalo, N. Y.

Application June 1, 1944, Serial No. 538,257

8 Claims. (Cl. 74—10)

This invention pertains to radio tuning mechanisms generally, and has for one of its several objects to provide an improved mechanical band-spreading tuning mechanism for general application to radio receivers.

Another object of the invention has to do with the provision of a mechanism of this character which embodies a two-speed dial arrangement which will cover the desired ranges and, at the same time, will provide sufficient geared-down vernier drive so that weak signals will not be passed over without hearing them.

A further object of the invention is to provide a mechanical band spreader of an extremely simplified design and construction that will eliminate the difficulties heretofore experienced in the manufacture of previously proposed types of such mechanisms, and which will be highly efficient in operation, comparatively inexpensive to make, and capable of being easily installed to change single speed tuning mechanisms into a two-speed type.

With these and other objects and advantages in view, the invention resides in the certain new and useful combination, construction and arrangement of parts, as will be hereinafter more fully described, set forth in the appended claims, and illustrated in the accompanying drawings, in which:

Figure 1 is a side elevation of the improved band-spreading mechanism and a tuning condenser mounted on the chassis of a radio receiver, in accordance with the invention;

Figure 2 is a front elevation of the band-spreading mechanism and showing the drive means therefor;

Figure 3 is a vertical section taken on the line 3—3 of Figure 1;

Figure 4 is a view identical to that of Figure 3, but showing the relative position of the parts after the drum has been rotated ninety degrees;

Figure 5 is sectional detail of the key device for switching the mechanism from regular tuning to band-spread tuning;

Figure 6 is an enlarged fragmentary section taken on the line 6—6 of Figure 5; and

Figure 7 is a front view of the dial drum, showing the rocker actuating cam and broached key-way for engaging the band-spread mechanism to the condenser shaft through the key.

Referring to the drawings, wherein like characters of reference denote corresponding parts throughout the several views, the embodiment of the invention, as is exemplified therein, is comprised in a shaft 12 having bearing in a frame

element 11 rising from the chassis B of a radio receiver, at the front side of the tuning condenser A. The shaft 12 has its rearwardly directed end coupled, as at 13, to the rotor shaft 5 of the condenser A, and is afforded added bearing support by collars 14 and 15 keyed to the same at the front and rear sides of the frame element 11.

Loosely mounted on the shaft 12, immediately 10 in front of the collar 14 is a drum 16, which is driven by a cable 17 having connection with the regular tuning dial (not shown) of the radio receiver. Fixed on the front side of the drum 16 is an eccentric or cam element 18 that is engaged 15 by a yoke 20 at the lower end of a rocker arm or lever 19, which has its upper end pivoted, as at 21, to a stud 22 projecting forwardly from the frame element 11; the stud 22 being provided with a sleeve 23 to space its forward end from 20 the frame element 11 a proper distance for the support of the rocker arm or lever 19 in its cooperative relation with respect to the eccentric or cam element 18.

Fulcrumed at its inner end on the shaft 12, immediately in front of the rocker arm or lever 19, is a second rocker arm or lever 24 and immediately in front of it is yet another or third rocker arm or lever 26, which has its inner end taking the form of a substantially semi-circular yoke 27 that is engaged over the shaft 12 and its outer end extending radially outward from the center of the arc defined by the curvature of the yoke 27 and slotted as at 28, outwardly from the latter for substantially its entire length. The side of the yoke 27, opposite the slotted arm 26, is angularly bent inwardly as at 27', and is pivoted at the center of the bent portion, as at 29, to the center of the lower side of the yoke 20 of the rocker arm or lever 19. The outer end of the rocker arm or lever 24 is provided with a pin 25 that is slidably engaged in the slot 28 to permit of relative movements between the arms or levers as required.

The drum 16 is normally rotatable with the shaft 12 through the medium of a key 30 that is pivoted, as at 31, within a slot 12' formed in the shaft 12 and, to such end, the inner end of the key 30 is provided with an angular offset or lug 32 which engages in a slot 16' in the hub 50 of the drum 16, when the key is normally disposed. The key 30 extends forwardly within the slot 12' to a point beyond the outer rocker arm or lever 26, where it is enlarged to the form of an isosceles triangle, as at 33, that has the 55 vertex portions of its longer side projecting from

opposite sides of the shaft 12. The rocker arm or lever 24 is to be connected to the shaft 12 when the drum 16 is disconnected therefrom, and to this end the key 30 is provided with a second offset or lug 34 which is projected from the slot 12' and into engagement with a slot 24' in the hub of the rocker arm or lever 24, whenever the key 30 is actuated to withdraw the offset or lug 32 from the slot 16' of the drum 16.

To actuate the key 30, to disconnect the drum 16 from the shaft 12 and to simultaneously connect the rocker arm or lever 24 thereto, an actuator or switching device, in the form of a second and smaller drum 35, is rotatably mounted on the front end of the shaft 12 and has a cam element 36 on its inner side for cooperation with the opposed end of the key, whenever the drum 35 is rotated by a cable 39 leading to the band-spread control (not shown) on the control panel of the radio receiver. Extending radially from the inner side of the drum 35 is an arm 37 that carries a pin 38 at its outer end for engagement in the slot 28 of the rocker arm or lever 26, inwardly from the engaged position of the pin 25 on the rocker arm or lever 24. Thus, with the dial drum 16 disconnected from the shaft 12, its rotative motion is transmitted to the shaft 12 through the cam and rocker arm or lever mechanism in a greatly reduced ratio in relative turning movements, but which ratio may be varied through a setting of the pin 38 on the radial arm 37 of the key actuator drum 35.

In the operation of the tuning control thus provided, and for regular signal reception tuning, the dial drum 16 will be connected to the shaft 12 by the key 30 being normally disposed so that the offset or lug 32 is engaged in the slot 16' in the hub of the drum 16, in which position of the key, the offset or lug 34 will be disengaged from the slot 24' of the rocker arm or lever 24. With this setting, the station selector dial of the radio receiver can be manipulated over the entire broadcast band and its motion will be transmitted to the rotor of the tuning condenser A by the cable 17, the drum 16 and the shaft 12, the rotative motion being substantially one hundred and eighty degrees.

Now, to change over to band-spread tuning, the actuator drum 35 will be rotated by the cable 39 from a band-spread control (not shown), on the control panel of the radio receiver, to move the cam element 36 into engagement with the opposed end of the key 30, when the latter will be rocked on its pivot 31 to withdraw the offset or lug 32 from the slot 16' of the dial drum 16 and, at the same time, move the offset or lug 34 into engagement with the slot 24' of the rocker arm or lever 24. With this position of the parts, the drum 16 is disconnected from the shaft 12 and its rotative motion is to be transmitted to the shaft 12, and the rotor of the condenser A, through the rocker arm or lever mechanism. Upon manipulation of the cable 17, from the station selector dial, the motion of the eccentric or cam 18 imparts an oscillatory motion to the rocker arm 19 and this motion is, in turn, imparted to the rocker arm or lever 26 at the pivot connection 29. Likewise, the resultant oscillatory motion of the rocker arm or lever 26 is transmitted to the rocker arm or lever 24 at the point of engagement of the pin 25, on the latter, with the slot 28 of the rocker arm or lever 26. The degree of oscillatory motion of the rocker arms or levers 24 and 26 can be varied by the setting of the pin 38 relatively to the slot

28 which is effected from the actuator drum 35 that has a maximum range of movement to adjust the pin 38 for rotative motion through an arc slightly greater than one hundred and eighty degrees. In any case, the amount of band-spread to be obtained will depend upon the dimensions of the inter-related parts of the mechanism.

Having thus fully described my invention, it is to be understood that various changes in form and minor details of construction may be resorted to, without departing from the spirit of the invention, or its scope as claimed.

What I claim is:

1. In combination, a tuning condenser for radio receivers and a control mechanism therefor, said mechanism comprising a shaft adapted to be connected to the rotor of the condenser a drum on said shaft, a cable on said shaft a cable connecting said drum with means for rotating said drum for effecting its normal low reduction operation for rough tuning, an eccentric cam element mounted on the front side of said drum, a yoke engaging said cam; said yoke having formed at the lower end of a rocker arm which is pivotally mounted for cooperative relation with respect to said cam, a second rocker arm pivotally mounted on said eccentric, and a third rocker arm pivotally mounted on said second rocker arm and said yoke said eccentric adapted to be connected to the condenser rotor for effecting its high reduction operation for fine tuning when said first control means is disconnected from said rotor, and means for disconnecting the first named control means from the condenser rotor and simultaneously connecting said eccentric thereto.

2. The combination as in claim 1, with the said mechanism adapted to be mounted on the chassis of a radio receiver and having means for supporting the shaft and coupling it to the rotor of the tuning condenser.

3. A mechanical control mechanism for the tuning systems of radio receivers, comprising means adapted to be connected to the rotor of the tuning condenser of a radio receiver for effecting its normal low reduction operation for rough tuning, an eccentric adapted to be connected to the condenser rotor and a plurality of rocker arms coacting with said eccentric for effecting its high reduction operation for fine tuning, and means for disconnecting the first named means from the condenser rotor and simultaneously connecting said eccentric thereto.

4. The mechanism as in claim 3, with the first named means and said eccentric in unit assembly with a shaft adapted to be coupled to the rotor of the condenser.

5. The mechanism as in claim 3, with the first named means having the form of a rotatable drum adapted to be actuated from the station selector dial of the radio receiver by a cable connecting said drum and said dial and the said eccentric and said rocker arms adapted to be actuated from the drum.

6. A mechanical control mechanism for the tuning system of a radio receiver, comprising a shaft in connection with the rotor of the tuning condenser of the receiver, a drum rotatably mounted on said shaft and adapted to be actuated from the signal selector dial of the receiver by a cable connecting said drum and said dial for effecting the normal low reduction operation of the condenser for rough tuning, a system of levers adapted to be connected to the shaft by means of an eccentric mounted on said drum, said ec-

centric adapted to actuate said system of levers for effecting a high reduction operation of the condenser for fine tuning, and means for disconnecting said drum from said shaft and simultaneously connecting one of the levers of said system thereto.

7. The mechanism as in claim 6, with the said eccentric taking the form of a cam element.

8. The mechanism as in claim 6, with said means taking the form of a key that is pivotally mounted in a slot in said shaft and a dial control for actuating the key.

CHARLES F. MATHEWSON.
